(57) **CLAIM**

The ornamental design for a pet separation anxiety device, as shown and described.

DESCRIPTION

FIG. 1 is a perspective view of a pet separation anxiety device according to my design;

FIG. 2 is front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of thereof.

The broken lines illustrate portions of the pet separation anxiety device that form no part of the claimed design.
